UNITED STATES PATENT OFFICE.

PAUL WENZEL, OF MILWAUKEE, WISCONSIN.

WALKING FIGURE.

Application filed December 4, 1923. Serial No. 678,497.

To all whom it may concern:

Be it known that I, PAUL WENZEL, a citizen of the United States, residing at Milwaukee, in the county of Milwaukee and,

5 State of Wisconsin, have invented certain new and useful Improvements in Walking Figures, of which the following is a specification.

This invention relates to theatrical or 10 showman's apparatus and more particularly to a walking figure.

The invention consists mainly in the provision of a figure mechanically connected to the body of the operator so that in operation the figure simulates walking or running. The impression given is that of a figure chasing the operator, the connections between the figure and operator being such that the figure participates in most of the 20 running and walking actions.

The details of construction of the invention will be made more apparent as this description proceeds, especially when considered in connection with the accompanying drawings wherein:

Figure 1 is a perspective view of a walking figure, constructed in accordance with this invention;

Fig. 2 is an enlarged fragmentary view, 30 partly in section;

Fig. 3 is a detail perspective view; and

Fig. 4 is an elevational view of the supporting harness.

Referring now particularly to the drawings wherein like reference characters indicate like parts, it will be noted that the figure is constructed to represent a human skeleton, the figure being constructed preferably of cork or other similar light non-fragile material, the figure including a backbone 10, to the base 11 of which there is connected a pair of legs 12, arms 13 being connected to the shoulder portions of the skeleton.

45 The thigh portions 14, of each leg, are connected to the body by means of hinges 15, whereby the thigh portions are capable of swinging movement both forward and backward, these hinges consisting preferably of leather hinge members 16 fitted into recesses 17, formed in the adjacent ends of the thigh portions 14 and the base 11. Connection between the thigh portions 14 and the lower leg portions 18, is provided by 55 flexible hinge members 19, so arranged as to permit a swinging movement of the lower

leg portions only in one direction. The feet 20 are connected to the lower leg portions 18 by hinges 21, similar to the hinge connections at the hips of the skeleton. 60

The arms 13 are hingedly connected as at 22 to the forearm portions of the arms 13, so as to swing in two directions, hinge members 23 being arranged at the elbows and hinge members 24 at the shoulder connections. Resilient cord-like members 25 extend from the wrist portions to points adjacent the shoulder hinges and resiliently hold the arms bent in the manner illustrated in Fig. 1. However, during the walking or running movements of the figure, these resilient suspending members and the hinge connections at the joints of the arm permit the arms to move in a manner simulating the action of the arms of a human being 75 when running or walking.

The neck 26 is hingedly connected to the head 27, as at 28, and the jaw 29 of the head is pivotally connected thereto by pins 30, the coil spring 31 being provided 80 which permits the jaw to open and close during the walking or running movement of the figure.

The figure is supported in an upright position and rearwardly of the operator by 85 means of a supporting rod 32, projecting rigidly from a supporting frame consisting of an upright member 33 adapted to be secured to the body 34 of the operator by means of straps 35, as clearly illustrated 90 in Fig. 1. A set screw 36 provides means for detachably connecting the rod 32 to the frame, this rod preferably passing through the breastbone of the skeleton and into the backbone or spine thereof. A supplemental supporting member, in the form of a wire 37, is detachably connected, as at 38, to the upper end of the member 33, and passes through the breastbone of the skeleton, and is also connected to the backbone 100 10 thereof.

Connected to each of the legs 12 immediately adjacent the knee hinges thereof is an operating flexible member 39, which is preferably in the form of a thin wire. 105 Each of these operating wires is provided with a loop 40 through which the arm of the operator may be inserted, as suggested in Fig. 1, so that as the operator runs or walks, and consequently swings his arms, 110 the legs of the skeleton will be lifted clear of the ground and moved in a forward posi-

tion and then permitted to again engage the ground, whereupon they will be moved rearwardly because of their engagement with the ground and the forward movement of the figure, thus simulating the walking or running, as will be immediately apparent.

Thus it will be obvious that as the operator walks or runs, the figure will participate in a movement simulating the movement of the operator's body. The weight of the figure is supported mainly, and the figure maintained in an upright position, by means of the supporting rod 32 and flexible member 37, as will be obvious, so that a movement of the operator's arms will, by reason of the flexible connection to the legs of the figure, move the same as though the figure were walking or running. Obviously, the arms will, because of the movement of the figure, move in a manner to resemble the manner of the movements of a human being's arms, while walking or running, but will be maintained substantially in the position illustrated in Fig. 1 by means of the resilient members 25. The head will also move relatively to the shoulders, by means of its hinge connection thereto, and as mentioned, the jaw will be caused to open and close.

While the invention has been described in some detail as embodying a figure representing a human skeleton, still it will be immediately apparent that the invention may be applied with equal facility to other types of figures, and that the figures need not necessarily simulate human figures.

Therefore, I reserve the right to make such changes as may come within the purview of the accompanying claims.

Having thus described my invention, what I claim is:

1. In an arrangement of the character described, a figure provided with jointed legs, means for supporting the figure spaced from the body of an operator and

means connected to the arms of the operator for actuating said jointed legs to simulate walking.

2. In an arrangement of the character described, a jointed figure including jointed legs, means including a body harness for supporting the same upon the body of the operator and spaced therefrom and means connected to the operator and controlled by him for causing the legs of the figure to move in a manner simulating walking.

3. In an arrangement of the class described, a figure simulating a human figure including jointed legs, a frame for supporting said figure in an upright position, means for connecting said frame to the body of the operator and flexible means connected to the arms of the operator and to the jointed legs of the figure for moving said legs in a manner simulating walking.

4. In a theatrical device of the character described, a figure simulating a human figure including jointed legs, arms, neck and a hinged jaw, a frame for supporting said figure in an upright position, means for detachably connecting said frame to the body of the operator and flexible connections between the arms of the operator and the legs of the figure, whereby when the arms of the operator are swung forwardly and rearwardly, the legs of the figure will be caused to move in a manner simulating walking or running.

5. In a theatrical device of the character described, a figure simulating the human figure provided with jointed arms and legs, means attachable to the body of the operator for supporting said figure in an upright position immediately behind the operator and means connecting the legs of the figure to the arms of the operator for causing said figure to move in a manner simulating walking or running.

In testimony whereof I affix my signature.

PAUL WENZEL.
